(57) CLAIM

The ornamental design for a jersey, as shown and described.

DESCRIPTION

FIG. 1 is a front elevational view of a jersey, showing my new design;

FIG. 2 is a right-side elevational view thereof;

FIG. 3 is left-side elevational view thereof;

FIG. 4 is a rear elevational view thereof;

FIG. 5 is a top plan view thereof; and,

FIG. 6 is a bottom plan view thereof.

Several figures, including FIGS. 1, 2, 3, and 6, show a pattern on the interior portion of the jersey which illustrates a surface texture of a wool-like material.

The broken lines illustrating surface ornamentation on the sleeves of the jersey form no part of the claimed design. The remaining broken lines illustrating stitching on the jersey form no part of the claimed design.
